UNITED STATES PATENT OFFICE.

CHARLES B. BUERGER, OF PITTSBURGH, PENNSYLVANIA, ASSIGNOR TO GULF REFINING COMPANY, OF PITTSBURGH, PENNSYLVANIA, A CORPORATION OF TEXAS.

APPARATUS FOR AND PROCESS OF DISTILLING OILS.

Application filed August 28, 1923. Serial No. 659,823.

This invention relates to apparatus for and processes of distilling oils; and it comprises a distilling apparatus comprising a horizontal cylindrical still body, means for heating such a body, means for removing vapors, means for feeding oil at one end and for removing oil at the other, internal means adapted to block out a portion of the chamber space and form arcuate uptake 5 passage ways next the wall in the lower portion of the body and a downtake passage way near the middle and perforated steam pipes within said arcuate passages; and it also comprises a method of distilling lubricating and other oils with avoidance or diminution of cracking wherein the oil to be distilled is caused to traverse a horizontal heated zone, passing from end to end therein with a forced up-and-down cyclic circulation by injected steam during its travel 10 said steam passing next the heated elements and a consequent helical progression; all as more fully hereinafter set forth and as claimed.

25 As has long been known, relatively heavy petroleum oils can be distilled in the ordinary types of fire heated still with the aid of injected steam at temperatures at which they would otherwise not boil or distil; and 30 in practice, lubricating oils, wax oils, etc., are customarily so produced. The effect of the steam is, theoretically, much the same as that of a vacuum in so far as a reduction of the boiling point or distilling temperature 35 is concerned.

In steam distillation of this type, the function of the steam is to reduce the boiling point and give increased area of evaporating surface (in the bubbles) and dilute 40 and carry forward the evolved oil vapors. It also serves as an agitating and circulating means. Ordinarily, the oil is contained in an externally heated still and the steam is delivered from perforated pipes near its 45 bottom. Often the still takes the form of a horizontal cylindrical shell in a furnace setting and the steam pipes are longitudinally placed along the bottom. The distillation-promoting effect of the steam is of course 50 only exercised locally at the points where it rises through the oil and the rest of the oil is not affected by the steam until circulation brings it into its path. In this circulation the oil passes along the walls of the still and 55 is there heated and thence goes into the path

of the steam where evaporation is effected. The steam does not rise in a path near the walls. The oil elsewhere is, so to speak, idle. As more or less cracking of the oil takes place at any high temperature, the amount 60 being proportional to the time of exposure to heat, the presence of this idle oil is, of course, not advantageous. Relatively quiescent bodies of oil, subjected to heat but not to agitation, become overheated, and deteriorate in quality.

In the present invention, these conditions are recognized. The horizontal cylindrical still is used because of its mechanical strength and convenience and because of the 70 ample vapor space offered in its upper portion above the normal oil level, but a large part of the space in the bottom, which would otherwise be occupied by oil out of the direct path of the steam, is blocked out 75 by a special liner; usually hollow and of sheet metal. The liner is spaced somewhat away from the still wall to give a quadrant-shaped oil chamber therebetween on each side and perforated steam pipes are located 80 therein. The effect of admitting steam is, of course, to project oil upwardly in these chambers or passages, which are usually rather narrow (of greater height than width); and to return this oil and to obtain 85 positive circulation, the liner is provided with a vertical middle passage, or passages, leading to the bottom of the still. The effect of this is to give a cyclic circulation of the oil to be distilled. It is convenient to make the liner of two parts, separating them by a comparatively narrow passage along the middle line.

Ordinarily, I desire to have the still continuously operating, feeding oil to be distilled at one end and removing residual oil at the other. In so doing, under the present invention, since the oil (considered as a main body) is traveling longitudinally of the still and since there is also 95 a cyclic up-and-down circulation of the oil in its progress, the net effect is a helical passage of the oil from end to end of the still. This much contributes to the effectiveness of the steam distillation; so to speak, it permits of a precise treatment of the oil, combining the positive longitudinal feed of the oil through the narrow tubular types of still with the convenience of the open and unobstructed vapor chamber of a 100 105 110

cylindrical shell still. The main body of oil passing through the still is subjected to a vertical cyclic circulation by means of the injected steam. The contact of steam and oil is positive and effective; and there is effective utilization of both of the evaporative and the circulatory functions of the introduced steam.

In the accompanying illustration, I have shown, more or less diagrammatically, certain apparatus within the present invention and suitable for use in performing the described process. In this showing

Figure 1 is a transverse vertical section through the still of Figure 2, taken along line 1—1, and shows diagrammatically the firing means employed: and

Figure 2 is a central longitudinal section along line 2—2 of Fig. 1.

20 In the showing, element 1 is a diagrammatically shown fire box and still setting. Depending within the housing is still 2, shown as a horizontal cylindrical shell still made, as usual, of boiler plate or the like. 25 The housing engages and supports the still in the usual way, along its middle line, leaving the lower portion exposed to the fire gases in the housing. As shown, within the still is located a liner below the normal oil 30 level shown and therefore submerged in the oil in the still. As shown, this liner is composed of two sections 3 and 4 made of sheet steel and hollow, these sections being of generally triangular section and each having 35 a curved outer surface 5, conforming in curvature to the curvature of the shell but located a sufficient distance therefrom to furnish a quadrant shaped passage 6 on one side of each section of the liner. The liners 40 or spacers are positioned by means of the turnbuckles 6^a and the links 6^b in the still. These quadrant shaped chambers afford free communication between the oil above the liner and the bottom of the still. Within 45 each of the quadrant shaped passages are located a plurality of perforated steam pipes 7 for admitting steam to the oil, these pipes extending the length of the still. Between the liner sections 3 and 4 is a vertical down- 50 take passage 8 of sufficient width to permit free circulation of oil. Oil to be distilled enters one end of the still (see Fig. 2) through inlet pipe 9 and residual oil leaves the other end of the still through exit pipe 55 10. The two pipes are so arranged as to preserve a normal oil level somewhat above the displacement chamber or liner. Vapors leave the still to go to a condenser (not shown) through exit pipes 11. Clean-out 60 manholes 12 and drainage pipe 13 are of the usual structure and for the usual purposes.

In the use of the structure shown and described, oil to be distilled enters continuously through the pipe line to submerge the

liners to the normal oil level shown. Steam is admitted through pipes 7 and rises in the quadrant shaped passages along the heated walls, producing a violent circulation and effective contact of steam and oil. The heat necessary for distillation is afforded by the firing means 1. The oil carried upward through the quadrant shaped passages flows over the top of the liner and downwardly through down-take 8 in cyclic circulation. Residual oil is finally discharged through 10. A cyclic up-and-down circulation being superimposed upon the forward movement of the oil through the still, the net result is a helical circulation.

This invention can be applied to existing commercial stills with a great improvement in their efficiency.

Steam inlet pipes 14 leading to the interior of the hollow liner sections and vent pipes 15 leading therefrom are intended for safety purposes. They may be used to steam out any oil vapors and oil which may accumulate by leakage into the spacing elements and avoid danger of explosion.

What I claim is:—

1. A steam still for petroleum oils comprising a horizontally disposed cylindrical shell, means for introducing oil at one end thereof, means at the opposite end for permitting the removal of oil, means disposed in the lower portion of the shell and blocking out a major portion of the volume thereof for forming longitudinal passages for the oil as it travels through the shell, said means comprising members having a continuous solid outer surface impermeable to the oil and being spaced from the lower wall of the shell, and means for admitting steam to the space between the shell wall and the members.

2. A steam still for petroleum oils comprising a horizontally disposed cylindrical shell, means for introducing oil at one end thereof, means at the opposite end for removing the oil, means for blocking out a substantial portion of the lower part of the shell, said blocking out means comprising spaced members extending longitudinally of the shell, spaced from the bottom and sides thereof, and having continuous imperforate surfaces, and means for introducing steam to the sides and bottom of the shell in the space between the shell and the blocking out members.

3. A steam still for petroleum oils comprising a cylindrical shell, means for admitting untreated oil thereto, means for removing treated oil therefrom, means within the shell for blocking out a major portion of the lower half of the shell, said means comprising closed members having an arcuate face slightly spaced from the curved wall of the shell and a pair of plane faces adjacent the arcuate face and at right angles

to each other, and a steam pipe for admitting steam to the space between the curved face of the blocking out means and the wall of the shell.

- 5 4. A steam still for petroleum oils comprising a horizontally disposed cylindrical shell, means for applying heat to substantially the lower half thereof, means for introducing oil at one end of the still, means 10 for removing oil from the opposite end, a main pipe for introducing steam to the still, branch pipes formed with apertures therein disposed along the curved lower wall of the still at opposite sides thereof and connected 15 to the main pipe, quadrant-shaped members disposed within the still, each member having a curved wall slightly spaced from the wall of the shell and extending from adjacent the vertical center plane of the shell 20 to adjacent the horizontal center plane thereof, and also having continuous plane walls extending parallel to the vertical and horizontal center planes respectively, the entire member being closed against the entrance of 25 oil.
5. In the distillation of oils, the process which comprises forming a plurality of thin annular parallel bodies of oil flowing in a closed ring, the adjacent bodies having a 30 common portion, heating the bodies on one side to cause an upward circulating flow, as-

sisting the flow by applying a jet of steam acting in the same circular direction, and maintaining the rotary flow thus developed in the bodies at substantially the same rate 35 of speed at all portions thereof to prevent the settling of carbon from the oil, and superimposing upon the annular flow a longitudinal flow, whereby all parts of the entire body of oil will be constantly moved at substantially the same speed and without the formation of local portions of relatively quiescent oil.

6. In distilling oils, the process which comprises passing a body of oil through a 45 cylindrical shell in a longitudinal direction with respect to the shell as a whole, dividing the oil in the shell into a plurality of annular bodies of oil flowing in a closed ring, said bodies being thin as compared to the 50 diameter of the annulus, heating the annular portions at that region which contacts with the cylindrical wall of the shell, applying steam to the bodies to cause their rotation in a direction transverse to the longitudinal 55 flow of the oil in the shell, and maintaining the circular flow thus induced at a high speed in all portions of the body of oil.

In testimony whereof, I have hereunto affixed my signature.

CHARLES B. BUERGER.
